PRESSING MACHINE

Original Filed June 18, 1927

UNITED STATES PATENT OFFICE

ERNEST DAVIS, OF SYRACUSE, NEW YORK, ASSIGNOR TO THE PROSPERITY COMPANY INC., OF SYRACUSE, NEW YORK, A CORPORATION OF NEW YORK

PRESSING MACHINE

Application filed June 18, 1927, Serial No. 199,857. Renewed March 29, 1929.

This invention relates to pressing machines such as garment or laundry pressing machines of the type set forth in my pending applications Serial Number 199,856, filed 5 June 18, 1927, and Serial No. 200,982, filed June 23, 1927, embodying an expandible pressure member which is expandible by internal pressure to apply heavy pressure after the press is closed, and it has for its object, power 10 means for closing the press and for applying internal pressure to the pressure member and a two-hand control, one of which controls the closing of the press and the other of which must be operated to apply the internal pressure 15 sure to the pressure member, or whereby both hands must be used to apply the heavy pressure.

The invention consists in the novel features and in the combinations and constructions 20 hereinafter set forth and claimed.

In describing this invention, reference is had to the accompanying drawings in which like characters designate corresponding parts in all the views.

25 Figure 1 is a side elevation of a machine embodying my invention.

Figure 2 is an enlarged sectional view through the pressure member and the means for controlling the application of internal 30 pressure thereto.

Figure 3 is a longitudinal sectional view through a portion of the power means for closing the press and the manual control therefor.

35 I have here illustrated my invention as applied to a conventional form of garment press or laundry press comprising an upper pressing element or head 1 movable toward and from a lower pressing element or buck 2 on 40 which is mounted a pressure member 3 of the construction shown in my pending application. This pressure member is expandible vertically toward the head 1 and may be formed of resilient metal or other material 45 such as rubber. It has an upper or top flexible wall 4 and its side walls are in the form of bellows so that the pressure member expands vertically under the influence of internal pressure. The pressure member is preferably 50 of reinforced rubber or other flexible mate-

rial, the rubber being reinforced by canvas layers. Usually, the top wall 4 is covered with a suitable padding 5. A fluid, and preferably a hydraulic or non-compressible liquid, fills the pressure member 3, and this fluid 55 fills feed pipe 6 to said member and fills a stand pipe or chamber 7 to the level of the liquid in the pressure chamber 3.

The head 1 is shown as carried by the usual lever 8 pivoted between its ends at 9 to a 60 standard 10 rising from the frame 11, and the buck 2 is mounted on a suitable bracket or goose neck 12 also mounted on the frame 11.

The means for actuating the head 1 to close the same or bring the head down lightly onto 65 the article to be pressed, comprises a suitable manually controlled motor and motion transmitting means between the motor and the head 1. The motor is here shown as a single acting cylinder 13 having a piston 14 movable 70 therein and the motion transmitting connections in addition to the lever 8 as here illustrated includes toggle links 15 and 16 pivoted together at 17, the link 15 being pivoted at 18 to the rear arm of the lever 8 and the link 75 16 being pivoted at 19 at its lower end to the frame.

In the illustrated embodiment of my invention, the link 16 forms a bell crank with a forwardly extending power arm 20 to which 80 the piston rod 21 is pivoted at 22. The cylinder is mounted to oscillate about a pivot 23. Obviously, during the out stroke of the piston 14, the toggle will be straightened and the press head 2 moved down toward the 85 head 3. The toggle is adjusted so that it moves into a dead center line when the head is down to its full extent so that the head is locked in its closed position. When the pressure is relieved in the cylinder, as will be hereinafter described, the press will be opened by 90 the reaction of a returning spring 24 connected to the power arm 20. The piston is preferably actuated by compressed air supplied from a suitable source through a feed 95 pipe 25 and the flow of air is controlled by a two-way valve which is operated by a manual.

26 designates the casing of the two-way valve, and the valve itself as here shown is a 100

slide valve including a normally closed intake valve head 27 and a normally open exhaust valve head 28 which are connected by a stem 29, the valves being held in their normal position by a spring 30 and by the air pressure. An intake and exhaust pipe 31 leads from the valve casing 26 from between the valve heads to the upper end of the cylinder 13. The valve is operated to open the intake head 27 and close the exhaust head 28 by any suitable manual here shown as a push button 32 which acts on a lever 33 which in turn acts upon a stem 34 of the exhaust valve head.

15 Obviously, when the button 32 is depressed, the exhaust valve 28 will be moved toward its seat and the intake valve 27 moved off its seat permitting air to enter the valve casing and through the pipe 31 to the cylinder 13 to actuate the piston on its power stroke until the toggle has moved into straightened position.

When the pressure is released in the pressure member as will be presently described, the spring 24 reacts and the air exhausts back 25 through the pipe 21, valve casing 26 out through the exhaust passage 35 providing, of course, that the operator is not holding down the button 32. But owing to the spring 24 acting to constantly open the press, the operator must hold the button 32 depressed until 30 internal pressure is applied to the pressure member 3 as will be presently described.

The power means for applying pressure to the pressure member is also compressed air 35 which is manually controlled. The manual control comprises a valve mechanism similar to that for controlling the closing of the press, but in addition, including means for holding the pressure applied as long as desired. The manual for controlling the flow 40 of air to the pressure chamber 7 and hence, to the pressure member 3 includes a valve casing 36 having a two-way valve 37 and 38 therein connected by a stem 39, the valve casing 45 being connected to a feed pipe 40 and by a pipe 41 to the upper end of the pressure chamber 7, the pipe 41 being connected to the valve casing between the valve heads 37 and 38. The valves are operated by means of a 50 push button 41* and lever 42, this lever 42 acting through an intermediate lever 43 for a purpose to be presently described. After the button has been depressed to open the intake valve head 37 and close the exhaust 38, the 55 two-way valve is held in its operated position indefinitely to suit the will of the operator by a pressure operated member as a diaphragm 44 located in a chamber 45, the chamber on one side of the diaphragm being connected by a passage 46 to the valve casing 36 between the valve heads. The diaphragm 60 acts upon a sliding stem 47 which coacts with the lever 43.

Obviously, after the pressure has been built 65 up in the chamber 7, it will build up in the

diaphragm chamber 45 actuating the diaphragm 44 to the left, Figure 3 to move the plunger 47 to the left and thus hold the valve heads 37 and 38 into the position to which they have been operated by the button 41. 70 To relieve the pressure in the pressure member 3, the air is exhausted from the pressure side of the diaphragm chamber 45 through a normally closed exhaust valve 47* located in the valve casing 48 which is connected by a pipe 49 to the pressure side of the chamber 45. The exhaust valve 47 is operated against the action of a returning spring by a lever or handle 50. Obviously, when this lever 50 is operated, the air will be exhausted from the 80 diaphragm chamber permitting the intake valve head 37 to close and the exhaust valve 38 to open so that the air pressure can exhaust from the pressure chamber 7 through the pipe 41, valve casing 36 and out through the exhaust passage 51. When this pressure is relieved, the spring 24 is free to react to open the head 1. It is held from reacting when the pressure is applied to the pressure member 3 by the fact that the toggle is held in 90 a straight line by the pressure which overcomes the spring 24.

In operation, the operator depresses the button 32 and thus brings the head 1 down onto the garment or other article on the padding 5 and holds the button down while he depresses the button 41 momentarily, a momentary depression of the button 41 only being necessary to create the pressure in the chamber 7. The manual means and the control valves are located in suitable housings carried at any convenient point on the frame 11.

What I claim is:

1. A pressing machine including cooperating pressing elements, one of which is movable toward and from the other, a flexible and expansible pressure member on one of said elements and substantially coextensive therewith, and formed with extendible sides, power means for moving the movable element toward the other element, a manual for controlling the operation of the power means, means for creating internal pressure in the expansible pressure member and a manual for controlling the latter means. 105

2. A pressing machine including a buck, a head movable toward and from the buck, a flexible and expansible pressure member mounted on the buck substantially coextensive therewith expandible toward the head and formed with a metal top wall, power means for actuating the head into engagement with the article on the pressure member, manual means for controlling the operation 120 of the power means and manual means for controlling the application of internal pressure to the pressure member. 125

3. A pressing machine including a buck, a head movable toward and from the buck, 130

- power means for actuating the head including a toggle movable into straightened position when the head is moved to its full extent toward the buck, a flexible and expansible pressure member on the buck substantially coextensive therewith and expansible toward the head, power means for applying internal hydraulic pressure to the pressure member and manual means for controlling the application of the last mentioned power means. 5
4. A pressing machine including co-operating pressing elements, one of which is movable toward and from the other, means for moving the movable element toward the other and holding it in its position assumed when opposite the other element, one of said elements having a flexible expansible pressure member associated therewith substantially coextensive with the same and formed with 10 extendible sides, and means for creating internal pressure in the expansible pressure member to expand the same and create pressure between said elements, and operator-operated means for controlling the pressure 15 creating means. 20
5. A pressing machine including a buck, a head movable toward and from the buck, means for actuating the head into a position opposed to the buck and for holding the head in such position, a flexible expansible power pressure member associated with the buck substantially coextensive therewith and formed with extendible sides, and operator-operated means for controlling the application 25 of internal pressure to the pressure member. 30
6. A pressing machine including co-operating pressing elements, one of which is movable toward and from the other, power means for moving the movable element toward the other into a position opposed to the other element and for holding it in said opposed position, one of said elements having a flexible expansible pressure member associated therewith and substantially coextensive with the same and formed with a pressing face which is movable bodily toward the other element when said pressure member is extended, and means for creating internal pressure in the 35 expansible pressure member to expand the same and create pressure between said elements when they are in opposed position, and operator-operated means for controlling the pressure means. 40
7. A pressing machine including a buck, a head movable toward and from the buck, means for actuating the head including a toggle movable into straightened position, power means for actuating the toggle toward straightened position, the head being opposed to the buck and in pressing relation thereto without applying substantial pressure when the toggle is in straightened position, a flexible expansible pressure member associated 45 with the buck and substantially coextensive therewith, power means for applying hy- 50
- draulic internal pressure to the pressure member, and operator-operated means for controlling the operation of the first power means and for controlling the application of internal pressure to the power member. 70
8. A pressing machine including a buck, a head movable toward and from the buck, an expansible pressure member mounted on the buck and formed with accordion walls so that said pressure member may be extended toward the head, power means for actuating the head into a position opposed to the pressure member without applying pressure thereto including motion transmitting parts arranged to lock the head in such opposed position before the expansible pressure member is expanded, manual means for controlling the operation of the power means and additional manual means for controlling the application of internal pressure to the pressure member. 75
9. A pressing machine including a buck, a head movable toward and from the buck, a pressure member mounted on the buck and expansible toward the head and collapsible away from the head, said pressure member being formed with a pressing surface and extendible sides, power means for actuating the head into a position opposed to the power member and out of pressing engagement therewith when the pressure member is collapsed including a toggle movable into straightened position and prevented from moving into straightened position upon the closing of the head when the expansible member is expanded, and manually controlled power means for applying internal hydraulic pressure to the power member. 80
10. A pressing machine including a buck, a head movable toward and from the buck, a pressure member mounted on the buck and expansible toward the head and collapsible away from the head, said pressure member being formed with a pressing surface and extendible sides, power means for actuating the head into a position opposed to the power member and out of pressing engagement therewith when the pressure member is collapsed including a toggle movable into straightened position and prevented from moving into straightened position upon the closing of the head when the expansible member is expanded, and manually controlled power means for applying internal hydraulic pressure to the power member. 85
11. A pressing machine including co-operating pressing elements, one of which is movable toward and from the other, an expansible and collapsible pressure member on one of said elements substantially coextensive therewith and expansible to move the entire top surface thereof toward the other element, manually controlled power means for 90
12. A pressing machine including a buck, a head movable toward and from the buck, a pressure member mounted on the buck and expansible toward the head and collapsible away from the head, said pressure member being formed with a pressing surface and extendible sides, power means for actuating the head into a position opposed to the power member and out of pressing engagement therewith when the pressure member is collapsed including a toggle movable into straightened position and prevented from moving into straightened position upon the closing of the head when the expansible member is expanded, and manually controlled power means for applying internal hydraulic pressure to the power member. 95
13. A pressing machine including a buck, a head movable toward and from the buck, a pressure member mounted on the buck and expansible toward the head and collapsible away from the head, said pressure member being formed with a pressing surface and extendible sides, power means for actuating the head into a position opposed to the power member and out of pressing engagement therewith when the pressure member is collapsed including a toggle movable into straightened position and prevented from moving into straightened position upon the closing of the head when the expansible member is expanded, and manually controlled power means for applying internal hydraulic pressure to the power member. 100
14. A pressing machine including a buck, a head movable toward and from the buck, a pressure member mounted on the buck and expansible toward the head and collapsible away from the head, said pressure member being formed with a pressing surface and extendible sides, power means for actuating the head into a position opposed to the power member and out of pressing engagement therewith when the pressure member is collapsed including a toggle movable into straightened position and prevented from moving into straightened position upon the closing of the head when the expansible member is expanded, and manually controlled power means for applying internal hydraulic pressure to the power member. 105
15. A pressing machine including a buck, a head movable toward and from the buck, a pressure member mounted on the buck and expansible toward the head and collapsible away from the head, said pressure member being formed with a pressing surface and extendible sides, power means for actuating the head into a position opposed to the power member and out of pressing engagement therewith when the pressure member is collapsed including a toggle movable into straightened position and prevented from moving into straightened position upon the closing of the head when the expansible member is expanded, and manually controlled power means for applying internal hydraulic pressure to the power member. 110
16. A pressing machine including a buck, a head movable toward and from the buck, a pressure member mounted on the buck and expansible toward the head and collapsible away from the head, said pressure member being formed with a pressing surface and extendible sides, power means for actuating the head into a position opposed to the power member and out of pressing engagement therewith when the pressure member is collapsed including a toggle movable into straightened position and prevented from moving into straightened position upon the closing of the head when the expansible member is expanded, and manually controlled power means for applying internal hydraulic pressure to the power member. 115
17. A pressing machine including a buck, a head movable toward and from the buck, a pressure member mounted on the buck and expansible toward the head and collapsible away from the head, said pressure member being formed with a pressing surface and extendible sides, power means for actuating the head into a position opposed to the power member and out of pressing engagement therewith when the pressure member is collapsed including a toggle movable into straightened position and prevented from moving into straightened position upon the closing of the head when the expansible member is expanded, and manually controlled power means for applying internal hydraulic pressure to the power member, and manually controlled power means for actuating the toggle toward straightened position. 120
18. A pressing machine including co-operating pressing elements, one of which is movable toward and from the other, an expansible and collapsible pressure member on one of said elements substantially coextensive therewith and expansible to move the entire top surface thereof toward the other element, manually controlled power means for 125
19. A pressing machine including a buck, a head movable toward and from the buck, a pressure member mounted on the buck and expansible toward the head and collapsible away from the head, said pressure member being formed with a pressing surface and extendible sides, power means for actuating the head into a position opposed to the power member and out of pressing engagement therewith when the pressure member is collapsed including a toggle movable into straightened position and prevented from moving into straightened position upon the closing of the head when the expansible member is expanded, and manually controlled power means for applying internal hydraulic pressure to the power member. 130

moving the movable element into a position opposed to the other element but out of pressing engagement therewith, and manually operable means for controlling the application of internal pressure to the pressure member to expand the same.

12. A pressing machine including co-operating pressing elements, one of which is movable toward and from the other, a flexible, expandable and collapsible pressure member on the latter element and substantially coextensive therewith and expandable to move the entire top surface thereof toward the former element, manually controlled power means for moving the movable element into a position opposed to but out of pressing engagement with the pressure member and holding it in said opposed position, and manually operated means for controlling the application of internal pressure to the pressure member.

13. A pressing machine including a buck, a head movable toward and from the buck, means for holding the head in position opposed to the buck after being moved from open position toward the buck, a flexible expandable power pressure member associated with the buck and substantially coextensive therewith and formed with extendible sides and a pressing face, and means for controlling the application of internal pressure to the pressure member.

14. A pressing machine including a buck, a head movable toward and from the buck, means for moving the head into and holding the head in a position opposed to the buck, the buck including an upward expandible portion substantially coextensive therewith and formed with extendible sides, and means for controlling the application of internal pressure to the expandible portion.

15. A pressing machine including a buck, a head movable toward and from the buck, the buck including an upper expandible portion substantially coextensive therewith and connected therewith by extendible side members, power means for actuating the head to bring it into a position opposed to the buck, an operator-operated control for the power means, operator-operated means for controlling the application of internal pressure to the expandible portion of the buck to expand the same toward the head.

16. A pressing machine comprising co-operating pressing elements, one of which has a closing and opening movement toward and from the other, means for locking the movable element in its closed position, an expandible pressure member on one of said elements for applying pressure between said elements when the movable element is in closed position, said member having a flexible pressure wall on its side opposed to the other pressing element and upwardly extensible side walls whereby the top wall is moved upwardly as a

unit and means for applying internal pressure to the expandible means.

17. A pressing machine comprising a buck, a head movable toward and from the buck, an upwardly expandible member on the buck having a flexible wall on its side toward the head and upwardly extensible side walls, a liquid in said member, means for locking the head in its down positions and operator-controlled means for applying pressure to the liquid in said member.

18. A pressing machine comprising co-operating pressing elements, one of said elements having a pressing surface and a hollow expandible pressure member substantially coextensive therewith for applying pressure between said elements, the pressure member having corrugated flexible walls perpendicular to the pressing surface of said element and means for applying fluid pressure to the interior of the hollow pressure member to expand the same.

19. A pressing machine comprising upper and lower cooperating pressing elements, one of said elements comprising a vertically expandible hollow pressure member substantially coextensive therewith, said pressure member having a pressing surface formed by the upper horizontal wall thereof and having pliant perpendicular side walls and manually controlled means for applying internal pressure to said hollow member to expand the same against the other pressing element.

In testimony whereof, I have hereunto signed my name, at Syracuse, in the county of Onondaga, and in the State of New York, this 14th day of June, 1927.

ERNEST DAVIS.
